his Attorney.

UNITED STATES PATENT OFFICE.

RUSSELL E. WAKELEY, OF ST. LOUIS, MISSOURI.

SAFETY-RAZOR.

1,199,132.

Specification of Letters Patent. Patented Sept. 26, 1916.

Application filed August 28, 1915. Serial No. 47,773.

To all whom it may concern:

Be it known that I, RUSSELL E. WAKELEY, a citizen of the United States, residing at the city of St. Louis, State of Missouri, have 5 invented certain new and useful Improvements in Safety-Razors, of which the following is a specification, reference being had to the accompanying drawing, forming a part thereof.

10 This invention relates to certain new and useful improvements in safety razors, the object of my present invention being to provide a comparatively simple and inexpensive razor especially of the kind stated having a reciprocating blade, whereby the act of 15 shaving is quickened and facilitated.

With the above and other objects in view, my invention resides in the provision of a 20 razor having a reciprocatorily movable blade and in certain novel features of form, construction, arrangement, and combination of parts, all as will hereinafter be described and afterward pointed out in the claims.

In the accompanying drawing, which 25 illustrates my invention in preferred form, Figure 1 is an elevational view of a safety razor embodying my invention; Fig. 2 is an enlarged fragmentary longitudinal sectional view through the same; Fig. 3 is an enlarged 30 elevational view of my new safety razor with several of the parts thereof in assembling position; Fig. 4 is a view taken approximately on the line 4—4, Fig. 2; Fig. 5 is a transverse sectional view taken through the 35 handle of the razor on approximately the line 5—5, Fig. 2, looking in the direction of the arrows; Fig. 6 is a plan view of the razor-blade forming part of my new razor; Fig. 7 is an inverted plan view of one of the 40 razor-blade guard-and-securing plates; Fig. 8 is a sectional view through the lower portion of the handle of the razor, showing in section the razor-blade reciprocating or actuating means; Fig. 9 is a view taken approximately on the line 9—9, Fig. 8; and Fig. 10 is a view taken approximately on the line 45 10—10, Fig. 8.

Referring to the said drawing, in which like reference characters refer to like parts 50 throughout the several views, 1 indicates a suitable tubular member of proper length, which is adapted to provide the main portion of the handle of my new razor. Fitting lengthwise in handle 1 with one end thereof, 55 which, for purposes of description, I will call the upper end thereof, projecting ex-

teriorly therefrom, is a rotatable rod or shaft 2, a bushing or the like 3 being preferably provided in handle 1 at the projecting end of shaft 2, as seen in Fig. 2. Fixed upon shaft 2 at its projecting upper end is a small arm or tappet 4, handle 1 at its upper end being provided preferably integrally with a pair of diverging or oppositely disposed obliquely outwardly presented arms 5—5 60 having perforated extensions 6—6.

7 indicates a suitable end or blade-securing plate, which is preferably, as is usual, transversely convexed on its outer face. Fixed upon the plate 7 at its opposite or inner face 70 is a pair of preferably square-headed threaded studs or bolts 8—8 adapted, when the several parts are operatively assembled, to project through handle-extensions 6—6 to receive securing-nuts 9—9.

10 indicates a suitable guard- and blade-securing plate, which is provided at its opposite lengthwise edges with dull or face-protecting teeth 11. Transversely plate 10 is provided with suitable perforations or 80 openings 12—12 adapted to freely accommodate the studs 8—8, plate 10 being further centrally and intermediate perforations 12—12 provided with an enlarged opening or aperture, as at 13, to accommodate the 85 passage through plate 10 to operative blade-engaging position when the parts are being assembled, of arm or tappet 4.

Adapted to operatively loosely or movably fit between plates 7 and 10, is a blade 90 14 approximately rectangular in shape in plan view, as illustrated in Fig. 6, blade 14 being sharpened to a cutting edge, as at 15—15, at both longitudinal sides. The body of blade 14 may be of any suitable thickness. Transversely blade 14 is provided with rectangular slots 16—16 to accommodate and fit the squared portions of studs 8—8, and centrally intermediate slots 16—16 blade 14 is provided with an enlarged 95 opening or aperture 17 within which tappet 4 is adapted to fit and work when the parts are operatively assembled. Extending into the area of opening or aperture 17 is a pair 100 of diametrically opposite teats 18—18, as clearly seen in Figs. 4, 5, and 6; aperture 17, instead of having a regular outline or perimeter circular in form, may thus be described as having a wall somewhat irregular or non-circular in outline. With the teats 18—18 or the otherwise so-called irregular 105 outline or wall of aperture 17 tappet 4 is

110

adapted to alternately engage, as shaft 2 is rotated, to reciprocate blade 14. It will be noted that, while blade 14 is of somewhat greater width than the width of outer or 5 end-plate 7, it is of somewhat less width than the width of inner or guard-plate 10 with its teeth 11, teeth 11 being adapted to protect the face from injury by the cutting edges 15 of blade 14 when the razor is in 10 service, as in the act of shaving, as will be well understood.

Suitably fixed upon handle 1 at its other or lower end, and surrounding the lower end of shaft 2, is a preferably cylindrical housing or casing 19. Projecting into housing 19 and loosely fitting in shaft 2 at its lower end, is a spring-winding button or the like 20, fixed upon the shaft of which within housing 19 is a ratchet-wheel 21. Loosely 25 mounted upon shaft 2 within housing 19, is a gear-wheel 23 having preferably a widened hub-portion 24. Arranged within housing 19 and surrounding hub-portion 24 of gear 23, is a spring-barrel or casing 25, provided within which is a suitable coil 30 spring 26, one end of spring 26 being fastened to casing 25 and its other end to hub-portion 24 of gear 23. Ratchet 21 and spring-casing 25 may be formed integrally or otherwise fixedly connected one with the other.

Mounted in suitable bearings 27 in housing 19, is a small shaft 28, fixed upon which to mesh with gear 23 is a pinion 29. Also 35 fixed on shaft 28 is a gear 30 adapted to mesh with a gear 31 fixed on main shaft 2, gear 31, in turn, meshing with a gear 32 mounted on a shaft 33 supported in suitable bearings 34 in housing 19.

40 In use or operation, the blade 14 with its securing and guard-plates 7 and 10 are operatively mounted on handle 1 by means of studs 8 and nuts 9, as will be clear, slots 16 permitting movement of blade 14 between said plates. With blade 14 in such position, tappet 4 fits in perforation 17 to engage with said projections 18. A pin 36 being now pressed inwardly to engage shaft 2 to frictionally prevent rotation of shaft 2, spring 45 26 is wound within its casing 25 through rotation of its winding-member 20. On pin 36 being released, as in the act of shaving, shaft 2, through said train of gearing described, will be rotated, whereupon blade 50 14, through alternate engagement of tappet 4 with said projections 18, will be reciprocated relatively to handle 1, the act of shaving being thereby quickened and facilitated.

Pivoted upon the lower wall of housing

19 is a pair of oppositely disposed spring- 60 pressed dogs 22 adapted to engage with the teeth of ratchet 21 to prevent reverse rotation of ratchet 21 and its connected spring- casing 25 under the influence or tension of 65 spring 26, and to prevent too rapid rotation 70 of shaft 2 under the tension of spring 26, I preferably provide in connection with gear 32 a centrifugal governor 35 of any standard or approved construction adapted to frictionally retard rotation of gear 32 and its connected gearing, as will be obvious.

I am aware that changes in the form, construction, arrangement, and combination of the several parts of my new razor may be made and substituted for those herein 75 shown and described without departing from the nature and principle of my invention.

Having thus described my invention, what I claim and desire to secure by Letters Patent is:

1. In a razor, a handle, an end-plate, studs on said end-plate connected to said handle, a guard-plate on said studs between said end-plate and handle, said guard-plate 85 having an opening, a blade movably mounted between said plates, said blade having slots for accommodating said studs, a central opening registering with the opening of said guard-plate, and a pair of diametrically opposite teats projecting into the area of its opening, a rotary shaft in said handle projecting at one end into said registering openings, an arm on said shaft fitting in the opening of said blade and adapted to alternately engage with said teats on rotation of said shaft, and means for rotating said shaft and its carried arm. 95

2. In a razor, a handle having a pair of diverging extensions, an end-plate, a guard-plate provided approximately centrally with an aperture, a blade movable flatwise between said plates, said blade having a pair of elongated slots and an aperture therebetween registering approximately with the 100 aperture of said guard-plate, a rotary shaft in said handle, an arm on said shaft fitting in the aperture of said blade to engage the wall thereof, studs on said end-plate projecting through said slots and engaging said 105 guard-plate and handle-extensions, retaining-members on said studs for securing said plates, blade, and handle operatively together, and means for rotating said shaft and its carried arm to reciprocate said blade. 110 115

In testimony whereof, I have attached my name to this specification.

RUSSELL E. WAKELEY.
